UNITED STATES PATENT OFFICE.

ERNEST E. HOWARD, OF KANSAS CITY, MISSOURI.

RAIL-LOCK.

1,232,179.

Specification of Letters Patent. Patented Feb. 24, 1920.

Application filed January 5, 1917. Serial No. 140,734.

To all whom it may concern:

Be it known that I, ERNEST E. HOWARD, a citizen of the United States, residing at Kansas City, in the county of Jackson and

5 State of Missouri, have invented certain new and useful Improvements in Rail-Locks; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to a combined rail lock and signal operating mechanism for movable span bridges, and more particularly to mechanism whereby track rails on a movable span may be locked to alining rails 20 on a permanent span leading thereto, to retain the alinement of the rails, the principal object of the invention being to provide effective means for accomplishing this purpose, together with mechanism for operating 25 the lock, a lock control device and means for operating a signal synchronously with the lock.

In accomplishing these objects I have provided improved details of structure, the preferred forms of which are illustrated in the accompanying drawings, wherein:

Figure I is a perspective view of portions of permanent and movable spans of a lift bridge equipped with my improvements.

35 Fig. II is a plan view of the same, showing the locking mechanism in locking relation to the track rails.

Fig. III is a side elevation of the same.

Fig. IV is a cross section on the line 40 IV—IV, Fig. II.

Fig. V is an enlarged detail perspective view of the joint in the operating lever rod.

Fig. VI is a detail perspective view of the automatic stop.

45 Referring more in detail to the drawings:

1—2 designate respectively, parts of permanent and movable spans of a lift bridge of any ordinary construction, carrying track rails 3—3', the ends of which terminate 50 closely adjacent each other and in longitudinal alinement when the movable span is in functional position.

The end of each of the rails 3 on the permanent span is incut to form a pocket 5 along its outer face and the end of each of the rails 3' on the movable span is incut and

provided with a joint plate 6, preferably welded to the rail and shaped to complete the rail and project therefrom so that when the movable span is lowered an extension 6' 60 of the joint plate will lie within the pocket 5 of the permanent rail 3 to form a continuous rail across the break between the fixed and movable spans.

7—7' designate plates which are fixed on 65 the fixed and movable spans adjacent the ends thereof and serve to firmly anchor the rail sections thereto, and 8—8' designate guard rails on the fixed and movable spans at the inner sides of the rails 3—3'.

70 Fixed on the permanent span adjacent the end of each of the rails 3 is a standard plate 9, having a bearing 10 therein, the channel of which registers with an aperture 11 in the end of the adjacent fixed rail 3 and an aperture 12 in the extension 6' of the joint plate on the movable rail 3'. Slidably mounted in said bearing 10 is a lock pin 14, the inner end of which is adapted for projection 75 through the registering apertures 11—12 in the rail and extension 6' to lock said rails together when the rail on the movable span is in functional position and the rails in operative alinement.

80 The outer end of the lock pin 14 comprises 85 a yoke 16 that is pivotally attached to the arm 17 of a three-way lever 18 pivotally mounted on a pin 19 rising from the plate 7 on the fixed span, so that it may turn horizontally when actuated in the manner presently described.

90 The lever 18 comprises an operating arm 21, the free end of which is pivotally connected with a pin 22 on a slide 23 that works 95 in a guide trough 24 on the fixed span, so that when the slide is moved longitudinally in its guide the lever is rocked to move the lock pin into or from the registering apertures in the fixed and movable rail members to connect or disconnect the same.

100 Each of the paired track rails 3—3' is identical in construction with the other, and each is adapted for connection by lock pins 14, the pins 14 on the side opposite the three-way lever 18 being controlled, however, by a single arm lever 25 which is pivotally mounted on a pin 26 on the fixed span 105 and connected through a transverse rod 27 with a third arm 28 of the three-way lever 18, so that when the three-way lever 18 is actuated to draw or throw the pin 14 110 from or into the rail apertures, the lock pin

14 at the opposite side of the span is operated synchronously with and relatively to the pin 14 at the operating side to lock or unlock the respective rails.

5 While I have shown but one end of the movable span with its rail locking parts, these parts are duplicated at the opposite end of the span and the rails at both ends of the movable span locked or unlocked 10 simultaneously through the operating lever that is preferably located at the center of the movable span.

The operating lever, 29, is rotatably mounted in a standard 30 located preferably 15 at the middle of the movable span and provided with a cross 31, having links 32 pivotally connected with its opposite ends so that when the lever is rocked in one direction the links are drawn inwardly to draw the locking pins and when rocked in the opposite direction the links are moved outwardly to throw the pins as presently described.

Pivottally connected with each of the links 32 is a connecting rod 33 which extends 25 along the movable span and is seated in guides 34 thereon, the outer end of the rod being pivotally connected with a link 35 which in turn is pivotally connected with a bar 36 that is slidably mounted in a guide 30 37 adjacent the end of the movable span in order that the bar may work longitudinally. The bar 36 is preferably provided with side rails 38 forming upwardly facing shoulders 39 and the guide 37 with keeper plates 40 35 that overlie said rails and bear against the shoulder 39 to retain the bar against vertical displacement while providing for free longitudinal movement thereof.

The bar 36 is upturned at its outer end 40 and provided with a connecting head 41 that lies parallel with the bar, but at a higher elevation, and is provided with a wedge shaped opening 42 that is adapted for receiving a reversely shaped lug 43 on the slide bar 23 45 that works in the guide 24 on the fixed span, so that when the movable span is lowered the head 41 will move over the lug 43 and form an operative connection between the draw bars on the fixed and movable spans, the 50 wedge shaped lug and opening insuring the proper positioning of the bars should there be any unevenness of alinement of the fixed and movable parts as the movable span comes to position.

55 In order to insure against premature or accidental throwing of the lock pins that would result in preventing the functional positioning of the rails on the movable span, I provide for automatically projecting a stop 60 into the pocket 5 in one of the fixed span rails, immediately upon the lifting of the movable span, to lie along the end of the aperture 11 therein and prevent movement of the locking pins 14 through the apertures 65 into the path of a descending rail member,

the action of the stop being automatic in its primary movement and yieldable under the weight of the descending rail so that it can be moved out of obstructing position upon the descent of the movable span. 70

The preferred construction of this stop or obstructing member comprises a lever 45 that is pivotally mounted on a bracket 46 suspended from the fixed span adjacent one of the rails thereon, one end of the lever being 75 provided with a weight 47 for automatically lifting the opposite end when unrestrained, and said opposite end carrying a stud 48 that is adapted for projecting upwardly through the floor of the span and along the rail 3 in 80 front of the aperture 11, so that when the movable span is raised and the extension 6' of the rail member 6 on the movable span moves away from its fixed mating member, the stud will automatically rise into the 85 pocket 5 to cover the aperture and prevent the projection of the locking pin across the path of the descending rail, the weight retaining the stud in this obstructing position until the movable span is lowered, when the 90 lower edge of the extension 6' engages the top of the stud and moves the same downwardly against the tension of its weight.

It is customary in bridges of this character to provide signals at the ends of the bridge 95 to indicate the position of the movable span, and in order to set the signals synchronously with the operation of the lock, I extend the slide bar 23 and provide the same with a connecting rod 50 that may run to the signal operating mechanism (not shown) so that when the operating lever is thrown to draw the locking pins preliminary to the lifting of the movable span, the signal will be set to indicate the opening of the bridge, and when 105 the lever is moved to throw the pins, the signal operating mechanism is actuated to return the signal to its "safe" position.

In using the mechanism, assuming the parts to be constructed and assembled as described, when the movable span is in functional position the ends of the rails are locked and the signal is properly set. Should it be desired to open the span, the bridge tender throws the lever 29, throwing 110 the connecting rods outwardly and moving the slides 23 to operate the three-way levers 18 at the inner ends of the permanent spans. This rocking of the three-way levers serves to draw the pins 14 with which they are directly connected and also to move the bars 27 that extend beneath the track and connect with the opposite levers 25, so that the pins 14 on both sides of the track are simultaneously moved outwardly to draw the same 115 from their locking connection with the extension 6' on the rail members on the movable span, thereby freeing said rail members, to permit the span to lift. This outward movement of the connecting rod also serves 120 125 130

to actuate the signal connecting rods 50 and set the signals to indicate an open span.

As the extension members 6' move upwardly the obstructing stud or stop 48 rises 5 under tension of its weight and moves over the end of the aperture 11 in the end of the rail 3 to form an obstruction that will prevent the throwing of the locking pin 14 should the operating lever be actuated before the movable span has returned to its functional position.

When the span is to be returned to its functional position it is lowered in the ordinary manner, and when it comes to place the 15 extensions 6' of the joint plates 6 move down along the ends of the rails 3 on the stationary span, the one at the side of the track where the obstructing stop is located engaging the top of the stop to move the same 20 downwardly against the tension of the weight 47, so that when the span is in place the lever may be operated to throw the locking pins as before described.

It is apparent that with this combination 25 of parts the track rails are normally securely locked together to form continuations of each other and that after the movable span has been raised the locking mechanism cannot operate until the movable span has completely returned to its functional position, thereby obviating incomplete placement of the span or shearing of the locking pins, and also serving to prevent accidental or erroneous setting of the signal at the end of the 30 bridge.

Having thus described my invention what I claim as new therein and desire to secure by Letters-Patent, is:—

1. In combination with normally alining 40 track rails, having side lapping ends provided with apertures, registering when the rails are in alinement, one of said rails being movable vertically relative to the other, a pin guiding and positioning standard adjacent the apertured portion of one of the 45 rails, a pin slidably mounted in the standard and movable into and from the apertures of both rails, and means for actuating the pin.

2. In combination with stationary and 50 vertically movable rail members, normally in longitudinal alinement and comprising side lapping portions, having transverse apertures registering when the rail members are in alinement, a pin guiding and positioning bearing having fixed relation to one of the 55 rail members, a pin in the bearing seating in the apertures of both rail members when the apertures are in registration and means for drawing the pin.

60 3. In combination with stationary and vertically movable rail members, normally in longitudinal alinement and comprising side lapping portions, having transverse apertures registering when the rail members are 65 in alinement, a pin guiding and positioning

bearing having fixed relation to one of the rail members, a pin in the bearing seating in the aperture of both rail members when the apertures are in registration, means for drawing the pin, and a stop movable across 70 the path of the pin when the pin is drawn.

4. In combination with stationary and vertically movable rail members, normally in longitudinal alinement and comprising side lapping portions, having transverse 75 apertures registering when the rail members are in alinement, a pin guiding and positioning bearing having fixed relation to one of the rail members, a pin in the bearing seating in the aperture of both rail members when the apertures are in registration, means for drawing the pin, and a stop located in the path of the pin when the pin is drawn and engaged by the other rail member to free the stop as the movable rail member returns to alinement with the fixed rail 80 member.

5. In combination with stationary and vertically movable rail members, normally in longitudinal alinement and comprising 90 side lapping portions, having transverse apertures registering when the rail members are in alinement, a bearing having fixed relation to one of the rail members, a pin in the bearing seating in the aperture of both 95 rail members when the apertures are in registration, means for drawing the pin, a stud located in the path of the movable rail member and movable into the path of the pin, means yieldingly urging the stud to 100 contact with the movable rail member, whereby the stud is caused to follow the said rail member across the path of the pin as the movable rail member moves out of alinement with the stationary member and 105 is engaged and shifted by the movable rail member as said member returns to alining position.

6. In combination with fixed and movable track supports, track rails, one on the fixed 110 and the other on the movable support, the movable rail having an extension movable along the fixed rail, a locking member movable in the rails to connect or disconnect the same, lever mechanism for actuating said 115 locking member comprising a rod having coöoperating heads on the fixed and movable supports to automatically break or make a joint as the movable member is raised or lowered.

7. In combination with fixed and movable track supports, track rails, one on the fixed 120 and the other on the movable support, a lock for said rails, means for actuating said lock, longitudinally movable members on the fixed 125 and movable supports, one having a lug and the other an opening for receiving said lug, whereby a joint is automatically broken or made between the rod members when the movable member is raised or lowered.

8. In combination with fixed and movable track supports, track rails, one on the fixed and the other on the movable support, a lock for said rails, means for actuating said lock, longitudinally movable members on the fixed and movable supports, one having a tapered lug and the other a tapered opening for receiving said lug whereby a joint is automatically broken or made between the 5 rod members when the movable member is raised or lowered.

9. In combination with fixed and movable track supports, track rails, one on the fixed

and the other on the movable support, a lock for said rails, means for actuating said lock, 15 longitudinally movable members on the fixed and movable supports, one having a lug and the other an opening for receiving said lug, whereby a joint is automatically broken or made between the rod members when the 20 movable member is raised or lowered, and guides on the supports for slidably actuating said rod members.

In testimony whereof I affix my signature.

ERNEST E. HOWARD.
